(57) **CLAIM**

We claim the ornamental design for a measuring instrument for measuring magnetic fields, as shown and described.

DESCRIPTION

FIG. 1.1 is a left side view of a measuring instrument for measuring magnetic fields showing our new design;
FIG. 1.2 is a right side view thereof;
FIG. 1.3 is a front view thereof;
FIG. 1.4 is a rear view thereof;
FIG. 1.5 is a top view thereof;
FIG. 1.6 is a bottom view thereof;
